UNITED STATES PATENT OFFICE.

EARL W. PAGETT, OF DETROIT, MICHIGAN.

CARBURETOR.

Application filed June 23, 1922. Serial No. 570,448.

My invention relates to carburetors or other apparatus for volatilizing liquids, especially oils, and has for an object to provide a simple and efficient apparatus for this purpose. Another object is to improve the methods whereby liquids are vaporized or carbureted.

To these and other ends, my invention may consist in a liquid fuel carburetor for 10 internal combustion engines, a single embodiment of which is shown in the drawings, wherein:

Figure 1 is a vertical section of a vaporizer or carburetor embodying my invention; 15 Fig. 2 is an elevation looking from the left of Fig. 1, of a fragmentary portion of the carburetor, parts being removed to disclose the jet chamber and fluid impeller;

Fig. 3 is a view similar to Fig. 2, showing the cover plate and shutter in place, and

Fig. 4 is a fragmentary section corresponding to Figs. 2 and 3, taken in the plane of the line IV—IV.

The apparatus of my invention, in its 25 present application may embody, in common with the usual types of carburetors, a throttle chamber 1 of any suitable form having an open end flanged or otherwise adapted for attachment to the engine port 30 or manifold, and a float chamber 2 including or adapted to include the usual float chamber mechanism and accessories. The throttle chamber is provided as shown in Fig. 1 with a butterfly throttle valve 3 rigidly mounted on the throttle valve shaft 4 which is adapted to be operated in the usual manner, either automatically or manually or both, for controlling and adjusting the engine speed and power output. For this 35 purpose a suitable throttle gear is usually provided. Within the float chamber 2 a constant level supply of fuel is stored for supplying the spray apparatus. The level of this liquid fuel is maintained by a float 5 operating a float valve 6 through the float lever 7 pivoted at 8. The supply pipe 9 is connected to the seat of the valve 6 by a union connection 10.

Two chambers are conveniently included 50 within the cylindrical casing 11 formed contiguously to the throttle and float chambers. One end, the entrance end of this casing communicates with the atmosphere or, if necessary with a duct or chamber supplying the gaseous constituent or vehicle of the mixture. The other end of the casing 11

discharges into the throttle chamber. The reason for this preference will presently be clear. At the entrance end of the generator casing, the spray chamber 12 is situated, the 60 conditioning chamber 13 is situated at the discharge end of the casing. The spray chamber provides a passage, which may be annular in form, for the air entering the carburetor. The liquid fuel jet is also 65 sprayed into this passage and thus the air and liquid fuel are initially brought together.

The liquid fuel is sprayed into the air in or passing through the spray chamber under 70 relatively high pressure. A fine division and high velocity of the jet is thus obtained. To this end a pump for drawing the fuel from the float chamber and forcing the atomized spray into the spray chamber is 75 provided.

This pump is best shown in Figs. 1 and 2 and is preferably of a positive flow rotary type. The cylindrical pump chamber 20 may be formed integral with the perforated 80 septum or partition wall 21 separating the spray and conditioning chambers. An impeller head 22, rigidly mounted on the pump spindle 23 journaled at 24 and 25, fits snugly and is rotatable within the pump 85 chamber. A plurality of scoop blades, or revolving ring pistons 26 are pivotally secured to the impeller head. These may be 90 yieldingly held outward by spring means, but this is not usually necessary, since centrifugal forces and the pressures incidental to the pump operation will hold their outer ends in contact with the peripheral wall of the pump chamber. These blades fit freely 95 but snugly within the pump chamber. The inlet duct 27 of the pump is provided with a feed tube 28 having an upwardly facing return bend at its lower end. The outlet or delivery duct 29 delivers the fluid from the pump to a spray orifice or nozzle under 100 pressure. Obviously a plurality or system of orifices or nozzles of various forms may be used, but a single simple orifice opening from the duct 29 into the spray chamber 12 and provided with the adjustable needle 105 valve 30, which both controls and spreads the fuel jet, has proven satisfactory. The delivery duct 29 is provided with a spring loaded by-pass or relief valve 31 communicating with the float chamber through the 110 by-pass duct 32. This automatically controls the spray jet pressure, permits the sur-

plus discharge of the pump to return to the float chamber or cistern, and guards against overloading the pump.

The pump spindle 23, passing through its bearing 25, carries the paddle wheel or fan 33 rigid and rotatable therewith. The adjacent end, 23^a, of this spindle is enlarged to accommodate a telescoping journal bearing for supporting the end of the pump spindle driving shaft 34, and is journaled in the hub 35. Rigid with the end 23^a of the pump spindle is a toothed driven clutch member 36. The corresponding clutch member 37 is mounted on the squared section 38 of the driving shaft 34 to be rotatably rigid but axially slidale thereon. The driving shaft is journaled at 39 and its outwardly extending portion is squared at 40 to receive the two halves 41 and 42 of the split V groove pinch pulley which engages with and is adapted to be driven by the bevel rimmed wheel 43. The compression spring 44 is adapted to insure a yielding frictional engagement between the pulley and wheel.

The wheel 43 is journaled on a stationary arbor 45 rigid with the body of the throttle chamber. This wheel is adapted to be mechanically driven from a rotating shaft of the engine to which the mixture generator 30 is applied. A flexible shaft 46 is accordingly shown coupled to the hub of the wheel and may be attached at its other end to the engine cam shaft.

For operating, i. e. engaging and disengaging the clutch members 36 and 37, and thus connecting and disconnecting the driving shaft 34 to the fan spindle; a clutch gear is provided. This may embody a yoke 47 swivel connected to the slidale clutch member 37 and rigidly secured at its other end to a plunger rod 48 slidably mounted in the throttle chamber body. To the outer end or head of the plunger rod, is secured a link or wire 49 which extends to a suitable manual or automatic control device whereby the clutch may be selectively engaged and disengaged. A compression spring 50 may be provided to normally hold the clutch in engagement.

The air inlet is provided for by the entrance apertures 51 through the outer end wall 52 of the casing 11 and for adjusting the size of these openings, a shutter valve or disc gate 53 is provided. The shutter 53 may conveniently be pivoted about a hub projecting from the outer face of the wall 52 and is held in place by the spring washer 54 secured by a screw 55. The ears 56 are provided as finger grips for convenience in manipulating the shutter to regulate the apertures 51.

The spray chamber 12 is supplied with air or other gaseous vehicle or charge compo-

nent through these entrance apertures and discharges into the conditioning chamber 13 through the marginally disposed apertures 21^a of the wall 21. The conditioning chamber in turn discharges into the throttle chamber 1 through the centrally disposed charge passage 13^a. The rotary paddle 33 serves as atomizing means for any liquid particles of the mixture which may enter the conditioning chamber.

Co-incidently with the piston movement in the engine to which the carburetor or mixture generator illustrated has been applied, the drive shaft 34 is rotated by its connections with the engine, and since the pump spindle is normally connected to its drive shaft, the pump and paddle are likewise rotated. Thus the suction or intake draft of the engine and the rotation of the pump and paddle system with their consequent functions normally occur simultaneously.

Any fluid substance not atomized or conditioned in the conditioning chamber may collect and drip back into the float chamber through the drip passage 57. A similar drip duct 58 is provided for returning the fluid products of condensation from the throttle chamber to the float chamber.

In addition to conditioning the charge generated, the paddle 33 may impel or assist in delivering the charge to the throttle chamber thus approaching in function or constituting a supercharge for the engine.

Having thus described my invention, what I claim is:

In a carburetor having a float chamber and a manifold connection above the float chamber and to one side thereof, a cylindrical casing on the float chamber of said carburetor and at one side of the manifold connection, said cylindrical casing having a wall formed in part by the manifold connection and an end wall and intermediate transverse partition, said partition dividing said cylindrical casing into a conditioning chamber adapted to receive air and adapted to receive fuel from said float chamber, and a spray chamber adapted to receive fuel from said conditioning chamber and discharge it into said manifold connection, a rotary fluid pump adapted to supply fuel to said conditioning chamber from said float chamber, a rotary paddle in said spray chamber adapted to force fuel into said manifold connection, and means axially of said rotary pump and said paddle and extending through said manifold connection and operable at the side of said manifold connection opposite said cylindrical casing for driving said pump and paddle.

In testimony whereof I affix my signature.

EARL W. PAGETT.
